United States Patent Office

Des. 199,838
Patented Dec. 22, 1964

199,838

MACHINE PAD

Nathan Hack, 537 San Vicente Blvd.,
Santa Monica, Calif.

Filed July 5, 1963, Ser. No. 75,671

Term of patent 14 years

(Cl. D9—6)

FIG. 1.

FIG. 5

FIG. 2.

FIG. 3.

FIG. 4.

FIGURE 1 is a perspective view of the machine pad of the present invention;

FIGURE 2 is a bottom plan view thereof;

FIGURE 3 is a side edge view thereof;

FIGURE 4 is an edge view taken from the bottom of FIGURE 2; and

FIGURE 5 is a fragmentary cross sectional view taken along lines 5—5 of FIGURE 2.

I claim:

The ornamental design for a machine pad, substantially as shown.
